UNITED STATES PATENT OFFICE.

SAMUEL MUNDHEIM, OF NEW YORK, N. Y.

DESIGN FOR A HAT.

42,438.

Specification for Design.

Patented Apr. 30, 1912.

Application filed February 1, 1911. Serial No. 606,053. Term of patent 3½ years.

To all whom it may concern:

Be it known that I, SAMUEL MUNDHEIM, a citizen of the United States, residing at New York city, in the county and State of New York, have invented a new, original, and ornamental Design for a Hat, of which the following is a specification, reference being had to the accompanying drawing, forming a part thereof, and in which—

I claim:

The ornamental design for a hat, as shown.

SAMUEL MUNDHEIM.

Witnesses:

MORRIS FRIEDMAN,
WILLIAM I. CROTTY.
